UNITED STATES PATENT OFFICE.

SAMUEL N. MURDOCK, OF COLUMBUS, OHIO, ASSIGNOR OF ONE-HALF TO
JOHN J. GALLAGHER, OF COLUMBUS, OHIO.

SMOKE-BELL HANGER.

No. 806,905.

Specification of Letters Patent.

Patented Dec. 12, 1905.

Application filed July 31, 1905. Serial No. 271,999.

To all whom it may concern:

Be it known that I, SAMUEL N. MURDOCK, a citizen of the United States, residing at Columbus, in the county of Franklin and State of Ohio, have invented certain new and useful Improvements in Smoke-Bell Hangers; and I do declare the following to be a full, clear, and exact description of the invention, such as will enable others skilled in the art to 10 which it appertains to make and use the same.

My invention relates to improvements in hangers for supporting smoke-bells above the burners or lamps upon a chandelier or 15 the like.

The object of the invention is to provide a simple, durable, and comparatively inexpensive device of this character which may be quickly and easily applied to either the stem 20 or the main pipe of a chandelier and from which any number of smoke-bells may be supported in any desired position.

With the above and other objects in view the invention consists of certain novel features of construction, combination, and arrangement of parts, as will be hereinafter 25 more fully described and claimed.

In the accompanying drawings, Figure 1 is a side elevation of a three-burner chandelier, 30 showing my improved hanger applied thereto and the smoke-bells supported from the same above the burners. Fig. 2 is a horizontal sectional view taken on the plane indicated by the line 2 2 in Fig. 1. Fig. 3 is a 35 perspective view of the clamping-band of the hanger removed from the chain; and Fig. 4 is a detail plan view, on an enlarged scale, of one end of the clamping-band.

Referring to the drawings by numeral, 1 40 denotes a chandelier, which may be of any desired form and construction, and 2 denotes smoke-bells which are supported above the burners of the chandelier by my improved hanger 3. This hanger consists of a band 4, 45 which is adapted to be clamped upon the stem, the main pipe, or any other portion of a chandelier or the like, and a plurality of supporting - arms 5, which are detachably connected to the clamping-band 4 and adapted 50 to support the smoke-bells 2. The clamping-band 4 is made from a strip of metal by forming in it transversely-extending parallel corrugations 6 and by cutting away or re-

cessing, as shown at 7, the upper end of each of the projecting portions of the corrugations, 55 so as to form parallel stop-shoulders 8. Each of the projecting portions of the corrugations, 6 forms a socket between it and the stem or pipe of the chandelier to receive the right-angularly-bent end 9 on one of the supporting-arms 5. These ends 9 are adapted to snugly fit said corrugations, and their right-angularly-projected portions 10 are adapted to enter between and engage the shoulders 8, so as to prevent the arms 5 from swinging or 60 turning. These arms 5 may be of any desired form and construction; but as shown they are curved or bowed longitudinally and have upon their outer ends hooks 11, which are adapted to engage eyes upon the bells 2. 70 The band 4 may be clamped upon the chandelier in any desired manner; but I preferably bend its ends outwardly to form parallel lugs 12 and form the latter with alining openings 13, one of which is screw-threaded to engage screw-threads upon a screw 14, which passes loosely through the other. It will be seen that when the screw 14 is turned in the proper direction the ends or lugs 12 will be drawn together to firmly clamp the band in 80 any desired position upon the chandelier. Owing to the fact that the corrugations 6 are numerous and arranged entirely around the chandelier, any desired number of the arms 5 may be employed, and they may be adjusted 85 so that the bells will hang directly above the burners of the chandelier.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of the invention.

Having thus described my invention, what I claim as new, and desire to secure by Letters Patent, is—

A smoke-bell hanger for chandeliers or the like, comprising a clamping-band, a screw for clamping the ends of said band upon a chandelier or the like, transversely-extending parallel corrugations formed in said band 105 and having their projecting portions at one

end cut away to form stop-shoulders, and a supporting-arm having a smoke-bell-engaging hook at one end and an angularly-bent portion at its opposite end adapted to enter one of the corrugations in said band and to engage said shoulders, whereby it will be prevented from turning, substantially as described.

In testimony whereof I have hereunto set my hand in presence of two subscribing witnesses.

SAMUEL N. MURDOCK.
